(57) **CLAIM**

The ornamental design for a foldable case for an electronic device, as shown and described.

DESCRIPTION

The present application is related to U.S. Design application Ser. No. 29/803,068 (now U.S. Design No. D991,239), filed on Aug. 10, 2021 all of which are entitled Foldable Case For An Electronic Device, the disclosures all of which are incorporated herein by reference.

FIG. 1 is a front perspective view of a foldable case for an electronic device, according to our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged portion of FIG. 1;

FIG. 10 is an enlarged portion of FIG. 1;

FIG. 11 is an enlarged portion of FIG. 3; and,

FIG. 12 is an enlarged portion of FIG. 3.

The broken lines of even length depict portions of the foldable case for an electronic device that form no part of the claimed design. The broken lines of uneven length identifying portions of the foldable case for an electronic device that are enlarged form no part of the claimed design. The
